UNITED STATES PATENT OFFICE.

GUSTAV W. JOHNSON, OF CHIPPEWA FALLS, WISCONSIN, ASSIGNOR TO CHIPPEWA FOUNDRY AND MACHINE COMPANY, OF CHIPPEWA FALLS, WISCONSIN, A CORPORATION OF WISCONSIN.

PUMP AND OPERATING MECHANISM.

1,364,995.

Specification of Letters Patent.

Patented Jan. 11, 1921.

Application filed August 19, 1919. Serial No. 318,460.

To all whom it may concern:

Be it known that I, GUSTAV W. JOHNSON, a citizen of the United States, residing at Chippewa Falls, in the county of Chippewa 5 and State of Wisconsin, have invented certain new and useful Improvements in Pumps and Operating Mechanisms; and I do hereby declare the following to be a full, clear, and exact description of the invention, such 10 as will enable others skilled in the art to which it appertains to make and use the same.

This invention relates to an improved pump and operating mechanism and the 15 principal object of the invention is to provide a pump having a plurality of pistons mounted in a pump cylinder and having independent operating rods and to further provide improved operating mechanism for 20 the pump whereby the pump rods may be moved in opposite directions. Another object of the invention is to provide this pump operating mechanism with an improved type of eccentric gearing for transmitting 25 motion from the driving shaft to the pump rods, the eccentric gears being so mounted that they will at all times remain in mesh with the gears of the driving shaft. Another object of the invention is to provide 30 an improved type of collar for supporting the eccentric gears from the driving shaft, the collar being so constructed that wear may be taken up. Another object of the invention is to provide an improved type of 35 cross head for connecting the pump rods with the pitman rod of the eccentric gears, the cross heads being so constructed and mounted that they will reciprocate freely without binding. Another object of the 40 invention is to provide an improved type of packing gland at the head of the pump cylinder and prevent leakage of water around the pump rods. Another object of the invention is to provide an improved type of 45 piston for the pump, the piston being so constructed that water may pass through the same when the piston is moving downwardly and then carried upwardly with the piston as the piston moves upwardly. Another object 50 of the invention is to provide an improved type of valve for permitting water to pass freely through the piston when the

piston is moving downwardly and preventing passage of water through the piston when the piston is moving upwardly. An 55 other object of the invention is to so construct this pump and actuating mechanism that a single set of eccentric gearing is sufficient for each piston. Another object of the invention is to so construct this pump and 60 operating mechanism that it will be comparatively simple in construction and comprise as few number of parts which will be strong and durable and not liable to easily break or get out of order. 65

This invention is illustrated in the accompanying drawings, wherein:

Fig. 1 is a front elevation of the entire pump and actuating mechanism.

Fig. 2 is a front elevation of the super- 70 structure or actuating mechanism for the pump,

Fig. 3 is a side elevation of the actuating mechanism for the pump,

Fig. 4 is a vertical sectional view taken 75 along the line 4—4 of Fig. 2,

Fig. 5 is a view of one of the collars for the eccentric gears,

Fig. 6 is a side elevation of the pump cylinder, the cylinder being partially broken 80 away to show the pistons positioned therein,

Fig. 7 is a side elevation of one of the pistons,

Fig. 8 is a vertical sectional view through 85 one of the pistons,

Fig. 9 is a perspective view of the valve used in connection with the piston,

Fig. 10 is a perspective view of one of the cross heads connecting the pump rods with the pitman rods extending from the eccentric 90 gears,

Fig. 11 is a plan view of the packing glands placed about the pump rods at the head of the pump cylinder,

Fig. 12 is a sectional view of the packing 95 glands.

This pump is provided with a pump cylinder indicated in general by the numeral 1 and positioned beneath the frame indicated in general by the numeral 2 and carrying 100 the operating mechanism by means of which the pistons positioned in the pump casing or cylinder may be reciprocated and moved vertically in the pump casing in opposite di-

rections. This pump and operating mechanism will be suitably mounted above a well with the frame 2 positioned above the upper end of the well and the cylinder extending 5 down into the well.

The pump cylinder or casing is provided with a barrel 3 which is open at its upper and lower ends and is provided at its upper end with a head 4 from the side of which 10 extends a neck 5 for connection with a pipe leading to a storage tank into which the water pumped will be stored. This head 4 is connected with the base of the frame 2 by means of suitable bolts and will register 15 with an opening formed in the base. This frame 2 is provided with side bars 6 which extend upwardly from the base 7 and are connected to provide bearings in which a shaft 8 will be mounted. A bracing yoke 20 9 is positioned intermediate the height of the frame to brace the side bars and overcome any tendency toward vibration which might be caused when the pump is in operation.

25 The driving shaft 9^a for the operating mechanism is rotatably mounted in bearings 10 upon the side bars and carries a pulley wheel 11 at one end about which a belt may be passed from a suitable source of power 30 and is provided at its opposite end with a fly wheel 12. Relatively small gears 13 are rigidly secured upon the shaft 9^a between the side bars and are protected by suitable shields or guards 14. These relatively 35 small gears 13 mesh with the relatively large eccentric gears 15 which are mounted upon the shafts 16 of the hanger brackets 17 mounted upon the shaft 8. These eccentric gears have their hubs extended outwardly 40 as clearly shown in Fig. 2 and carry collars 19 which are formed in sections 19^a and 19^b as shown in Fig. 5 connected by the bolts or other adjustable fasteners 20. Spacing strips 21 may be positioned between the ad- 45 joining portions of the sections so that the collars may be adjusted to the proper fit about the extensions of the gear hubs and suitable adjustment made when the collars or hub extensions have worn. The section 50 19^a is provided with an extension or neck 22 from which extends threaded pins or bolts 23 which pass through the sectional bearings 24 and hold the bearings in engagement with the collar and further hold the sections 55 of the bearings about the shaft 9^a. A spacing strip 25 will be provided between the bearing block 24 and the outer end of the neck 22 thus permitting proper adjustment to cause the collars to operate properly when 60 the machine is in operation.

Within the lower portion of the frame there has been provided rods 26 and 27 which extend upwardly from the center plate 28 of the base 7 to the brace or bridge 65 9 and provide means for slidably mounting

the cross heads 29 and 30. These cross heads will be each formed from sections 31 and 32 which are secured together by bolts 33 thereby coupling the sections of the cross heads about their respective guide rods so 70 that the cross heads will be slidably mounted upon the guide rods. Stub shafts 34 extend from the cross heads and are engaged by the bearing heads at the lower ends of the pitman rods or shafts 35 which extend upwardly through the spacing yoke 9, as clearly shown in Fig. 2, and are provided at their upper ends with bearing heads or collars 36 fastened about the stub shaft 37 of the eccentric gears 15. It will thus 75 be seen that as the driving shaft 9^a is rotated, the cross heads will be vertically reciprocated and it will be further seen that since the eccentric gears are set with the stub shafts thereof upon opposite sides of the 80 central point, the cross head 30 will be caused to move upwardly while the cross head 29 is moving downwardly and, therefore, the pistons of the pump, to be herein-after described, will be moved in the pump 85 cylinder in opposite directions.

Within the barrel or cylinder 3 of the pump casing 1 there is provided the upper and lower pistons indicated in general by the numerals 38 and 39 and connected with 90 the lower ends of the pump rods 40 and 41, the pump rod 40 being tubular and receiving the pump rod 41 which extends upwardly into the base portion of the frame and is connected with the arms 42 of the 95 cross head 30. The tubular pump rod has its upper end connected with a cross plate or connecting head 43 through the medium of a nipple 44, the plate 43 being positioned within the head 4 of the pump casing and 100 connected with the lower ends of the connecting rods 45 which extend upwardly and have their upper ends connected with the arms 46 of the cross head 29 upon opposite sides of the rod 41 and arms 42. The pump 105 rod 41 and connecting rods 45 extend through the stuffing boxes 47 of the packing gland box 48 secured to the center plate of the base 7 and it will be readily seen that this packing gland box forms a closure for 110 the upper end of the head 4 as well as providing means for preventing leakage of water about the rods 41 and 45 when the packing glands 49 are tightened to compress the packing within the stuffing boxes 115 47 about the rods. It should be noted that this packing gland is in the form of a plate having the sleeve at each end extending therefrom for fitting into the stuffing boxes about the rods and that this plate is pro- 120 vided with openings through which the pins 51 may pass thus permitting securing nuts carried by the pins to engage the side portions of the plate when the securing nuts 125 are tightened.

The pistons or pump heads which are mounted in the cylinder or barrel 3 are similar in construction and therefore a description of one will suffice for both. This 5 piston is provided with a hollow tubular body 52 which is provided at its upper end with an abutment collar 53 and is connected with the neck 54 by a web 55 positioned within the tubular body as shown in Fig. 10 8. This neck 54 is provided with an outstanding annular flange 56 forming an abutment collar for limiting downward movement of a valve to be hereinafter described and in order to provide a valve seat 57 the 15 upper portion of the collar 53 has been beveled. Cups 58 which are formed of leather or other suitable material are placed upon the tubular body 52 and are held in spaced 20 relation by the spacing rings 59, as shown in Fig. 7. The securing ring or nut 60 is screwed upon the threaded lower end portion of this tubular body and when tightened will form a strong and rigid pump piston or head which will fit snugly within 25 the cylinder 3. From an inspection of Fig. 8 it will be readily seen that water may pass upwardly through the tubular body and out through the spaces between the webs 55, the rush of water through these heads 30 serving to unseat the valve which is slidably mounted upon the neck and normally seats upon the valve seat. This valve 61 fits upon the valve seat 57 and is cut interiorly to conform to the valve seat and carries arms 62 which lead from the collar 63 slidably mounted upon the neck 54. It should be noted that the abutment collar 56 is cut to provide a continuation of the valve seat 57, as shown at 57', and that the 40 valve will seat firmly upon this valve 57' as well as upon the valve seat 57 thereby completely closing the spaces between the webs 55 and preventing water from passing down through the piston when the piston is moving upwardly. Suitable couplings 64 will be provided to connect the pump piston or head with the pump rods. When it is necessary to make repairs or insert a new suction pump it is simply necessary to remove 45 the securing ring or nut 60 and the pump can then be readily removed. If it is desired to grind the valve or valve seat, the piston can be disconnected from the pump rod. 50 When in use this pump will be set up over the well with the pump cylinder extending down into the well and having its open lower end connected with a pipe leading down into the well below the water line. A belt from a motor will be passed 55 around the pulley wheel 11 and when the motor is started the driving shaft 9 will be rotated and rotary movement transmitted to the eccentric gears 15 through the medium of the smaller gears 13 carried by the

driving shaft. The eccentric gears will be retained in mesh with the smaller gears through the medium of the collars 19 and since these eccentric gears are supported by the hanger bearing brackets 17, as shown, 70 sufficient play will be permitted to prevent binding when the pump is in operation. As the eccentric gears rotate the pitman shafts 35 will be reciprocated vertically and vertical reciprocating movement thus imparted 75 to the cross heads 29 and 30, the cross head 29 moving upwardly while the cross head 30 is moving downwardly. A similar movement will be imparted to the pump rods 40 and 41 and it will thus be seen that the 80 pistons will reciprocate in the cylinder 3 in opposite directions. Therefore as the lower piston moves downwardly water will pass upwardly through this piston and as the lower piston moves upwardly the valve will 85 close and this water above the lower piston will be drawn upwardly and will pass through the upper piston into the upper portion of the cylinder. As the lower piston moves downwardly to obtain a fresh 90 supply of water, the upper piston will move upwardly and its valve will close and the water in the cylinder above the upper piston will be forced upwardly and out through the neck 5 into the conduit pipe which will 95 lead to a tank or to any point where it is desired to have the water delivered. A very efficient pump has therefore been provided of the double-action type in which the desired movement can be imparted to the two 100 pistons with a minimum amount of actuating mechanism. There has further been provided a pump which is very simple in construction and which is not liable to easily get out of order.

105

What is claimed is:

1. A pump and operating mechanism comprising a frame, a pump cylinder positioned beneath the frame, a driving shaft rotatably connected with the frame, a supporting shaft carried by the frame, hanger bearing brackets carried by the supporting shaft, eccentric gears rotatably supported by said hanger bearing brackets, gears carried by the driving shafts, collars fitting loosely 110 about the hubs of the eccentric gears, necks extending from the collars, bearings carried by the necks and fitting about the driving shaft, cross heads slidably mounted in the frame, pitman rods connected to the eccentric gears and with the cross heads, pistons slidably mounted in the pump cylinder, and piston rods extending from the pistons and connected with the cross heads.

2. In a pump and actuating mechanism 125 including a frame, a drive shaft rotatably connected with the frame, hanger brackets pivotally supported in the frame, gears eccentrically connected with the hanger brackets, gears carried by the driving shaft, col- 130

1
lars loosely fitting about the hubs of the eccentric gears, necks extending from the collars, bearings adjustably connected with the necks and fitting about the driving shaft, 5 spacing means between the necks and bearings, cross heads slidably mounted in the frame for vertical reciprocating movement, and pitman rods connected with the cross heads and eccentrically connected with the 10 eccentric gears.

3. In a pump and actuating element including a frame, a driving shaft rotatably connected with the frame, eccentric gears rotatably suspended in the frame for eccentric 15 rotary movement, gears carried by the driving shaft and meshing with the eccentric gears, collars loosely fitting about the hubs of the eccentric gears, necks extending from the collars, pins extending from the necks, adjustable bearings fitting upon the pins and about the driving shaft, spacing elements positioned between the bearings and the necks, pump actuating cross heads slidably mounted in the frame, and pitman 20 rods having their lower ends loosely connected with the cross heads and their upper ends eccentrically connected with the eccentric gears.

4. In a pump and actuating element including a frame, supporting rods extending vertically in the frame, cross heads slidably mounted upon the supporting rods, arms extending from the cross heads with the arms of one cross head positioned upon opposite 35 sides of the arms of the second cross head, rods connected with the arms and extending beneath the frame, and means carried by the frame for imparting vertical reciprocating movement to the cross heads.

40 5. In a pump and actuating structure including a frame, cross heads slidably mounted in the frame, an arm extending from one cross head, arms extending from the second cross head upon opposite sides of the first 45 mentioned arm, rods connected with the arms and extending beneath the frame, and

means carried by the frame for imparting reciprocating movement to the cross heads.

6. In a pump and actuating mechanism including a frame, cross heads slidably mounted in the frame for vertical reciprocating movement and positioned upon opposite sides of the vertical center of said frame, arms extending inwardly of the cross heads, one cross head having a single arm and the second cross head having a pair of arms extending upon opposite sides of the arms of the first mentioned cross head, rods connected with the arms and extending beneath the frame, and means carried by the frame for imparting reciprocating movement to the cross heads. 50 55 60

7. A pump actuating mechanism including a frame, a cross head slidably mounted upon the frame and provided with a pair of relatively spaced arms, a second cross head slidably mounted upon the frame in spaced relation to the first cross head and provided with an arm extending to pass between the arms of the first cross head, the horizontal 65 70 distance between the cross head inlet being less than the combined lengths of said arms.

8. A pump actuating mechanism including a frame, a cross head slidably mounted upon the frame for vertical reciprocating movement, a second cross head slidably mounted upon the frame for vertical reciprocating movement and moving in a plane substantially parallel to and in spaced relation to the plane of the first cross head, arms 75 80 extending from the cross heads and extending in overlapping relation as the cross heads pass in moving, and means for imparting reciprocating movement to the cross heads. 85

In testimony whereof I affix my signature in presence of two witnesses.

GUSTAV W. JOHNSON.
